UNITED STATES PATENT OFFICE.

JOSEPH BOYLAN, OF BRADFORD, ENGLAND.

SHEET-FEEDING APPARATUS.

SPECIFICATION forming part of Letters Patent No. 653,207, dated July 10, 1900.

Application filed December 10, 1898. Serial No. 698,888. (No model.)

To all whom it may concern:

Be it known that I, JOSEPH BOYLAN, a subject of the Queen of England, residing at 98 Rupert street, Bradford, England, have invented certain new and useful improvements in apparatus for successively feeding sheets of paper or the like to printing and similar machines, of which the following is a specification.

10 This invention relates to improvements in mechanism or apparatus for successively feeding sheets of paper or the like to printing and other machines.

In the accompanying drawings, Figure 1 represents a side frame of an ordinary letter-press printing-machine and certain other parts, with my improved feed mechanism applied thereto. Fig. 2 is a plan view of certain of the parts shown in Fig. 1. Fig. 3 is a plan view, on a larger scale, of the feed mechanism. Fig. 4 is a cross-section of the same on the broken line *a b*, Fig. 3. Fig. 5 is a front view, partly broken away to economize space, and without the feed-board. Fig. 6 is a side view. Fig. 7 is a continuation to the right of Fig. 6, and Fig. 8 is a plan view of the same. Figs. 9 and 10 are detail views of the connecting-piece *K*.

The inclined feed-table *A* is supported by 30 chains *A*² *A*² and the antifriction-rollers *A*⁵, secured to its ends and running in the corner-guides *A*⁵, formed in the side frames *A*⁶ *A*⁶ of the feed mechanism. The chains *A*² run over the guide-rollers *A*⁷ and over the sprocket-wheels *B* on the lifting-shaft *B*², mounted in bearings *B*³ in the side frames *A*⁶. An inclined plate *A*⁹ extends across the machine close to the inner edge of the table, and the edges of the pile of sheets of paper represented by the broken lines *P* bear against it and are more or less "feathered" thereby. An adjustable curved or rounded separating-pad *C*, preferably made of india-rubber, projects from the top of the plate *A*⁹, and the function of the rounded portion of the pad being to still further "feather" the sheets as they pass onto it. For compactness and convenience of adjustment the separating-pad may be pivoted to the plate *A*⁹ and be supported by the arm *C*², projecting from the shaft *C*³, and the shaft may be slightly turned to adjust it by the screw *C*⁴, engaging the

55 arm *C*⁵, rigidly fixed on the shaft. The end of the arm bears against the spiral spring *C*⁶, carried by the projection *C*⁷ on the inside of the frame *A*⁶.

Above the pad *C* a quadrant or sector *D* is mounted upon the rocking shaft *D*², and a feed-roller *E* is provided on each side of the quadrant. These rollers are fixed upon the 60 ends of a shaft or spindle *E*², mounted upon a spring-arm *E*³, projecting into the opening *D*³ made through the quadrant. The arm *E*³ is pressed down by the spring *E*⁴, more or less compressed between the nut *E*⁵ on the 65 spindle *E*⁶, resting upon the arm and the projection *D*⁴ on the quadrant. A ratchet-wheel *E*⁷ is fixed upon the shaft *E*², which engages the pawl *E*⁸, pivoted upon the arm *E*³, so that when the quadrant moves toward 70 the sheets of paper *P* the rollers *E* roll freely over the pad *C* and the edge of the paper resting thereon; but on the return stroke the rollers are prevented by the pawl from rotating. Consequently the uppermost sheet is drawn 75 off and its edge brought over the first tape-roller *F*, which is in rotation, and, in conjunction with the rollers *E*, completely draws off the sheet of paper and passes it onto the tapes. The vibration of the quadrant *D* is 80 sufficient to move the rollers *E* from the position shown to one immediately over the tape-roller, with which they coöperate to pass the paper completely onto the tapes. The feed-rollers *E* are preferably made with an outer 85 covering of india-rubber *e*, as shown in Fig. 4, with an annular cushion *e*², of spongy rubber, beneath, mounted upon a wooden or other suitable boss *e*³, fixed upon the shaft *E*². A spring, cork, or other suitable rubber or 90 scraper *G* is provided to lightly bear upon the periphery of the roller *E* to preserve the clinging nature of the rubber face.

The quadrant *D* during its movement presses more or less upon the paper and also 95 while the sheet is withdrawn, thus tending to hold back against the pad *C* all the sheets excepting the upper one.

The rocking shaft *D*² is rocked by its arm *D*⁵, carrying an antifriction-roller *D*⁶, engaging 100 a cam-groove *D*⁷, formed in the inner face of the wheel *D*⁸, which wheel is driven in the manner hereinafter described.

The table *A* is lifted to gradually raise the

pile of sheets P as they become reduced in height by the rotation of the sprocket-wheels B, raising the chains A², having balance-weights i on the free end. The lifting-shaft 5 B², upon which the wheels are mounted, is driven by the ratchet-wheel B⁴, the pawl B⁵ of which is pivoted on the lever B⁶, loosely mounted upon the shaft B², and this lever is vibrated by the rod B⁷, coupling it to the stud 10 B⁸, fixed in a collar d on the shaft D². To prevent the pawl moving the ratchet at every stroke, the inclined pendent arm H is loosely mounted on the shaft B² and carries a star or roller H² at its free end, which rests upon 15 the pile of sheets P. This arm has a screw H³, adjustably fixed in the projection H⁴, and at each backward movement of the pawl B⁵ the end of the screw engages a projection B⁹ on the pawl and prevents said pawl falling 20 into the next tooth of the ratchet until the pile of sheets beneath becoming so reduced the arm H is lowered to such an extent that the pawl falls into the next tooth before its projection B⁹ engages the screw H³. The 25 roller H² is preferably made more or less star-shaped, so that when it is rotated by the withdrawal of a sheet the vibration thereby created tends to assist in "feathering" the sheets.

30 As a further means of feathering the sheets I employ a vibrating stroker or finger J, the free end of which bears upon the sheet when it moves toward the feed-rollers E, and it is lifted more or less out of contact with the 35 paper during its reverse movement. The stroker J is pivoted to the end of the arm J² on the cross-stay J³, which is actuated by the stud J⁴ on the quadrant D engaging the slot J⁵ in the arm J⁶, connected to J². This stay 40 also carries two bearing-arms K, in which the shaft K² is mounted, and the arm K³ on this shaft is coupled by the rod K⁴ to the end of the stroker J. The shaft K² is rocked to raise and lower the stroker by its arm K⁵, to the 45 end of which the connecting-piece K⁶ is coupled. The connecting-piece K⁶ has a forked end K⁷, embracing the shaft N, and the cam K⁸ on such shaft engages the projection K⁹ on the connecting-piece to actuate it. Figs. 9 50 and 10 represent two views of the connecting-piece.

To register the position of the sheets laterally, the tape-rollers or their equivalent as well as the bottom lay are moved longitudinally to bring the side of the sheet against the side lay or stop. For this purpose the cam O is provided on the shaft N to reciprocate the rod O², which is made with a slot fitting the shaft N and is provided with an antifriction-roller O⁴ to engage the cam. The 55 stud carrying the roller O⁴ is fixed by the setscrew O⁵, and when it is required to work the other lay it is simply necessary to reverse the position of the stud and roller to the other side of the rod, so that it can engage the other cam O⁶. The other end of the rod O² is coupled to the lever R on the stud R², and the

other arm R³ of the lever is bent down and engages the slide-piece R⁴, the inner end of which is made with claws R⁵ to clip into the groove F² in the bottom tape-roller F³. An arm S on the bottom lay-rod S² is connected to the slide R⁴ and causes the rod to move with the slide. A spring S³, stretched between a pin S⁴ on the rod S² and a pin S⁵ in the rod-bearing S⁶, is provided to return the parts to their normal position and keep the antifriction-roller O⁴ against its cam.

The wheel D³ is driven by the rod T from a crank T² on the cam-shaft T³ of the printing-machine. The rod T is coupled in the middle by the link T⁴ to the fixed stud T⁵, and a stud T⁷, fixed in the opposite end of the rod, engages a short radial slot T⁶ in the wheels D³.

To enable the feed to be readily stopped, 85 the slot T⁶ is not directly made in the wheel D³, but is formed in the arm U, loosely mounted upon the shaft N, and is coupled to the shaft by the pawl U³ engaging the projection U⁴ on the disk U⁵, rigidly secured to the shaft. 90 The pawl is held in position by the internal spring-pin U⁶, bearing against the flat U⁷. This permits the pawl to spring back against the disk U⁵ after it has been sufficiently moved to disengage it from the projection U⁴; but 95 if moved a little more than that it remains disengaged.

If it is only required to feed a sheet every alternate revolution of the cam-shaft T³, the triangular piece W mounted on the stud W² 100 and driven by the ratchet W³, is provided. The ratchet-wheel is driven by the pawl W⁴, mounted upon one arm of the lever W⁵, mounted upon the stud W⁶, and the other arm of the lever is coupled by the rod W⁷ to 105 the link T⁴ and is vibrated thereby. The parts are so arranged that at every alternate movement of the ratchet W³ the piece W engages the projection W⁸ on the pawl U³, and by disengaging it from the projection U⁴ prevents the wheel D³ from being driven.

The tape-roller F is driven by the wheel D³, and to intermittently stop the tape-rollers a portion of the wheel D³ is made without teeth and is provided with a concentrically-curved projection F⁴, which as it moves past the roller engages one of the curved sides F⁵ of the check-piece F⁶ on the roller-shaft and holds it stationary until F⁴ has passed.

The operation of the feeding mechanism is 120 as follows: A pile of sheets P is placed on the table A and the height of the latter is adjusted so as to bring the front edge of the uppermost sheet level with or slightly higher than the commencement of the pad C. The pad C is 125 adjusted to such a position in relation to the quadrant D that when a sheet of paper is passed between them the quadrant presses lightly upon it with sufficient pressure to practically prevent two sheets passing together—that is to say, the pressure of the pad upon the second sheet prevents it passing along with the upper sheet. When the machine is put into action, the stroker K, operat-

ing on the top of the pile in a somewhat-similar fashion to the ordinary hand-stroker, presses the upper sheets forward up the curved or inclined face of the pad in a finely feathered state. As soon as the uppermost sheet is sufficiently advanced in this way the rollers E engage its edge and draw it forward onto the tape-roller F, which is then in rotation, and the sheet is completely drawn off by the united action of the tape-roller and the rollers E. In this way the sheets are successively fed onto the tapes F⁷, and the pile of sheets is gradually raised by the above-described table-lifting mechanism to keep the top of the pile at a practically-uniform level. The motion of the tapes F⁷ is continued after the front edge of the sheet reaches the usual front gages F⁸, and the above-mentioned longitudinal motion is imparted to the tape-roller F⁸. This gives a lateral movement to the tapes, but as they are still in motion the pressure of the front edge of the sheet against the front gages prevents the sheet moving laterally with the tapes until the side lay F⁴ engages the side of the sheet. Then the united action of the side lay and the lateral movement of the tapes are sufficient to move the sheet sidewise to the extent of the inward movement of the side lay. In this manner each sheet is successively brought into exactly the same position. When the sheet is printed on both sides, the lay F⁵ is used when the second printing takes place, so that the same edge of the sheet is used for registering it laterally for both printings.

I claim—

1. In combination, the table, the quadrant D, means for moving the same, the rollers E carried by the quadrant and bearing upon the paper, means carried by the quadrant for pressing the rollers onto the paper and the pawl and ratchet for holding the roller against movement in one direction, the said quadrant also bearing on the paper to hold back all of the sheets excepting the top one of the pile, substantially as described.
2. In combination, the table, the quadrant carrying the bearing-roller, means for moving the quadrant, the feathering-finger J, the vibrating arm carrying the same, the pin on the quadrant engaging a part on the vibrating arm for operating the same, the rod K⁴ for raising the finger connected thereto and means for raising and lowering the rod K⁴, substantially as described.

3. In combination, the table, the quadrant for feeding the paper sheets off from said table and means for operating the quadrant comprising the shaft N, the arm U loosely mounted thereon, a pawl U³, engaging a projection connected with the shaft N and automatically-operating means for throwing said pawl out of operation, substantially as described.

4. In combination, the table, the quadrant, means for lifting the table comprising a pawl-and-ratchet mechanism, controlling means bearing on the paper pile to throw the pawl out of operation, means for operating the quadrant, a pawl controlling said means and means for throwing the pawl out of operation, substantially as described.

5. In combination, the table, the quadrant, the rock-shaft D² for rocking the quadrant, the gear-wheel D⁸ having a cam-groove, the arm D⁵ on the shaft D² engaging a cam-groove in the wheel D⁸, a pawl carried thereby and means for operating the wheel D⁸ comprising the pawl with means for throwing it out of operation consisting of the star-wheel with means for operating the same, substantially as described.

6. In combination, the table, the quadrant, the gear D⁸ having a cam-groove, means operated thereby for rocking the quadrant and the tape-roller having a check-piece, the said wheel D⁸ having a toothed portion and a plain portion, the latter of which engages the check-piece to hold the tape-roller from movement, substantially as described.

7. In combination, the table, the quadrant, means for oscillating the same comprising the pawl and disk with projections, and the loose arm carrying said pawl, the rod T connected to the arm, the crank for reciprocating the rod, the star-wheel controlling the pawl and means controlling the star-wheel consisting of the link T⁴ and the rod W⁷ connected to the star-wheel and to the link, substantially as described.

8. In combination, the tape-roller, the claws engaging a groove therein and a cam with connections to the claw for moving the tape-roller longitudinally, substantially as described.

In witness whereof I have hereunto set my hand in presence of two witnesses.

JOSEPH BOYLAN.
